M. BUCHHOLZ

PROTECTION OF ELECTRIC APPARATUS

Original Filed Sept. 15, 1922

Inventor:
Max Buchholz

by Attu.

UNITED STATES PATENT OFFICE.

MAX BUCHHOLZ, OF CASSEL, GERMANY.

PROTECTION OF ELECTRIC APPARATUS.

Original application filed September 15, 1922, Serial No. 588,457, and in Germany April 10, 1922. Divided and this application filed April 16, 1925. Serial No. 23,675.

My invention has reference to a method and means for protecting electric apparatus operating in an insulating liquid, such as oil transformers, oil switches, grounding 5 throttling coils, resistances and the like, and it is one of the important objects of my invention to provide a device of very simple construction and great reliability, and adapted to operate before extensive injuries 10 to the apparatus to be protected can occur by sparking, overloading or other disturbances.

My invention is particularly based on the fact that in the case of disturbances in the operation of the apparatus to be protected 15 or in the case of sparking or other irregularities of operation, or whenever such irregularities are imminent, as well as in the case of any ebullition or fermentation processes in the oil, serving as an insulating liquid, bubbles of gases of decomposition are formed which can operate a protective means, for instance an electric contact, either a working or a closed contact, which is adapted to switch out of circuit the apparatus 20 to be protected, or which will operate an alarm or annunciator device indicating the disturbance, or which is adapted to effect both kinds of operations. The gases formed by decomposition may influence the protective means in different ways, this application being a division of my copending application Serial Number 588,457 filed September 15, 1922.

I may for instance utilize a variation of 35 the pressure in the insulating liquid occurring in consequence of the unnormal conditions of working mentioned above to vary the operative conditions of the protective circuit.

A protective device embodying this invention is illustrated in the drawings annexed to this specification by way of example in a purely diagrammatic manner in elevation.

In the drawings *a* is an oil filled transformer casing, *b* is the core of the transformer, *c* are the windings, *d* are the leading-in insulations for the conductors. *B* is an alarm inserted in the protective circuit supplied with current by the source of current *g*. *k* are the terminals of the protective circuit facing a diaphragm *A* mounted in the side wall of the transformer casing *a* and capable of bridging the terminals and closing the protective circuit whenever an increase

of pressure within the casing *a* forces the diaphragm *A* outwards. Obviously, even a very insignificant increase of pressure within the casing *a*, due to an unnormal operation of the transformer, which results in the generation of heat or liberation of gases or vapors within the insulating liquid, will suffice to force the diaphragm *A* outwards and against the terminal contacts *k*, thereby actuating the alarm *B*, which may however also be replaced by some other annunciator or by an oil switch or the like for throwing out of the transformer.

The circuit to be controlled by the contacts referred to may excite either directly or by the medium of an intermediate relay 70 the releasing coil of an oil switch which interrupts the endangered circuit. In the case of apparatus the circuit of which does not include an oil switch, as frequently occurs, for instance in the cases of transformers 75 mounted in the field at wide distances apart, other provisions should be made for the purposes of this invention.

Besides the form of construction herein shown and described, the invention is susceptible of a variety of other modifications and forms of application of the principle of my invention all of which operate substantially in a similar manner. The means of connecting the contacting device with the releasing circuit and the switching means are open to changes and alterations without any material importance for the operation of the apparatus according to my invention which in its broad aspects comprises the operation 90 of safety devices for electric apparatus or the like, adapted for operation by vapors, fumes, gases or similar emanations liberated and expelled from the insulating medium, and means adapted to be operatively influenced by such emanations, and connected to fuses or equivalent safety means, the instrumentalities shown and described in this specification as embodiments of these principles being susceptible of modifications without deviating from the spirit of my invention as set forth in the claims.

In the claims the term "gases" is meant to comprise also vapors and fumes.

I claim:—

1. Protective system for liquid-insulated electric apparatus comprising a container and a supply of insulating liquid, surround-

ing the apparatus to be protected, a protective circuit and means adapted to be operated by a variation of pressure occurring in the insulating liquid in consequence of a decomposition of such liquid, for varying the operative conditions of said circuit.

2. Protective system for liquid-insulated electric apparatus comprising a container for said apparatus, a supply of insulating liquid completely filling said container and surrounding said apparatus, a protective circuit, a yielding wall forming part of said container and a contact device adapted to be operated by a deformation of said wall for

varying the operative conditions of said circuit. 15

3. The method of controlling abnormal working conditions of liquid insulated electric apparatus which comprises causing a decomposition occurring in the insulating liquid in consequence of such abnormal conditions to vary the pressure in said liquid, and causing such variation of the pressure to vary the operative conditions of a protective circuit. 20 25

In testimony whereof I affix my signature.

MAX BUCHHOLZ.
